UNITED STATES PATENT OFFICE

JOSEPH F. HUEBSCH, OF MIAMI, FLORIDA, ASSIGNOR TO HUEBSCH MANUFACTURING COMPANY, OF MILWAUKEE, WISCONSIN, A CORPORATION OF WISCONSIN

CLOTHES-STRETCHING APPARATUS

Application filed June 29, 1929. Serial No. 374,834.

The invention relates to clothes-stretching apparatus and more particularly to an apparatus for use in stretching handkerchiefs and the like prior to ironing.

5 The general object of the present invention is to provide a device of simple construction for firmly holding at one edge a group of handkerchiefs of varying sizes so that the operator may stretch the same while so held.

10 More particularly the invention is designed to provide a novel form of clamping mechanism in which one of the jaws is readily yieldable to accommodate the clamping in a group of handkerchiefs of different sizes and hence 15 different lengths so that they may be readily stretched in one operation, said yieldable clamping jaw being in the form of a tensioned belt preferably associated with a yieldable or cushion pad.

20 A further object of the invention is to provide a clamping apparatus of the type above described in which the yieldable jaw is the fixed jaw and cooperates with a relatively stiff or unyielding, movable jaw which is 25 normally urged against the yieldable jaw by spring pressure and is moved to open position by the operator.

20 The invention further consists in the several features hereinafter described and more particularly defined by claims at the conclusion hereof.

30 In the drawings Fig. 1 is a side elevation view of a device embodying the invention, parts being broken away and parts being shown in section;

35 Fig. 2 is a front elevation view, parts being broken away;

Fig. 3 is a top plan view of the device;

40 Fig. 4 is a detail sectional view taken on the line 4—4 of Fig. 1;

45 Fig. 5 is a detail sectional view taken on the line 5—5 of Fig. 4.

50 Referring to the drawings, the numeral 6 designates the supporting frame, here shown in the form of a hollow pedestal provided with a clothes tray 7 on its top portion, said pedestal being provided with a boss 8 apertured to receive the supporting lever 9 of the movable jaw 10 and carrying the pin 11 upon which said lever is intermediately pivoted.

The movable jaw 10 is preferably a rigid plate of wood, metal or other suitable material having a bevelled work-engaging face 12 which is preferably faced with a strip 13 of fabric.

55 Upon the front side 14 of the tray 7 is secured a channelled metal frame 15 having rollers 16 pivotally mounted thereon adjacent its ends. A belt or strip 17 of woven fabric or fabric and rubber composition, or other suitable pliable material is anchored at one end 18 on the frame 15 and passes around one of the rollers 16, thence across the frame around the other roller 16 and at its end 19 is secured to a coupling member 20 connecting it with one end of a spring 21 whose other end carries a threaded coupling 22 with which a rod 23, passing through one end of the frame, has threaded engagement. Thus the strip 17, yieldingly stretched under the tension exerted by the spring 21 between the rollers 16, forms a relatively fixed 60 but yielding jaw and preferably is associated with a backing pad 24 of rubber or other suitable yielding material, the tension of the strip 25 being adjusted by screwing the rod 23 in or out with reference to the coupling 22 to thereby increase or decrease the tension of the spring. The strip 17 and pad 24 are disposed in an inclined position to match up 70 with the bevelled face 12 of the movable jaw which is bevelled to facilitate the positioning of the work thereon. The width of the jaw 17 is about the same as the width of the face 12 of the movable jaw. The pad 24 is 75 secured to inturned flanges 25 on the frame 15 and preferably is about half the length of the movable jaw but centrally disposed relative thereto, the portion 26 of the jaw 10 extending parallel to the front face of the pad, while the end portions 27 of said jaw taper slightly 80 rearwardly, as shown in Fig. 4.

85 The inner end of the lever 9 is disposed in the hollow pedestal and is connected by a pin 28 to a coupling member 29 having a lug 30 connected by threaded rods 31, turnbuckle 32 and forked coupling 33 to a crank arm 34 secured to an oscillatory shaft 35 journalled in the lower portion of the pedestal and carrying a foot-treadle lever 36 projecting from the 90 95 100

frame at one side thereof within convenient reach of the operator of the machine.

The movable jaw is normally urged to a closed position by springs 37 disposed on opposite sides of the treadle linkage and anchored at one end to lugs 38 on the frame and connected at their other ends to headed rods 39 passing through apertured lugs 40 in the coupling member 29 and adjustably secured thereto by nuts 41 whose adjustment serves to vary the tension of the spring 37 and hence the force exerted by the movable jaw against the work.

When the operator receives the handkerchiefs from the extractor they are damp and compressed into crumpled wads. The operator then takes one handkerchief at a time and straightens one edge, using both hands, and then places this edge between the clamping mechanism which has been opened by depressing the treadle 36 to overcome the pressure of the springs 37. She then removes her hands and releases the foot treadle so that the jaws clamp this one edge of the handkerchief and with this edge held tight she proceeds to straighten the other three edges of the handkerchief by simply pulling taut the two free corners thereof. The operator then allows this edge to fall and repeats the operation with another handkerchief without removing the first handkerchief, so that a series of superimposed handkerchiefs, indicated by the numeral 42 in Fig. 1, are held clamped between the jaws and successively operated upon, it being noted that the edges of the handkerchiefs in this assembled group are clamped between the relatively rigid faces of the movable jaw and the belt 17, the pressure exerted upon the movable jaw acting to move belt against the pad 24. From forty to fifty handkerchiefs can be straightened in this manner without removing the individual handkerchiefs after each operation and preferably only when the entire batch is straightened when all the handkerchiefs are removed at one time. As the pad is of a length to accommodate all smaller sized handkerchiefs and as the larger sized handkerchiefs projecting beyond the pad are firmly clamped between the flexed belt and the portions 27 of the movable jaw, all the handkerchiefs of the group, regardless of size, are firmly held at one edge so that the operator may successively pull on the free corners thereof to stretch them.

The tray 7 is used for receiving the work, either before or after being subjected to the stretching operation.

The frame is preferably provided at the rear with a pair of spaced wheels 43, to readily move the same about the laundry, and with adjustable feet 44 on the opposite side.

The above described machine will readily and expeditiously handle quite a number of

handkerchiefs in one operation, the yielding belt jaw insures a uniform clamping engagement and but a single adjustment is necessary for this jaw.

I desire it to be understood that this invention is not to be limited to any particular form or arrangement of parts except in so far as such limitations are included in the claims.

What I claim as my invention is:

1. In a device of the character described, the combination of a frame, a tensioned strip of pliable material mounted on and spaced from said frame and forming a yieldable jaw, and a movable, relatively rigid jaw cooperating with said yieldable jaw to retain the work between them. 75

2. In a device of the character described, the combination of a frame, a tensioned strip of pliable material mounted on and spaced from said frame and forming a yieldable 85 jaw, a cushioning pad forming a backing for said strip, and a movable, relatively rigid jaw cooperating with said yieldable jaw and pad to retain the work between them.

3. In a device of the character described, the combination of a frame, a relatively fixed but yieldable jaw mounted on and spaced from said frame in an inclined position, and a movable, relatively rigid work-supporting member mounted on said frame and having a 90 bevelled edge cooperating with said yieldable jaw to clamp an edge portion of the work therebetween. 95

4. In a device of the character described, the combination of a frame, a pair of spaced 100 guides mounted on said frame, a strip of pliable material extending over said guides and forming a yieldable jaw, spring means for holding said strip under tension, a pad of cushioning material forming a backing for 105 the medial portion of said strip, and a movable jaw cooperating with said yieldable jaw to clamp the work therebetween.

5. In a device of the character described, the combination of a frame, a pair of spaced 110 rollers mounted on said frame, a strip of pliable material extending over and between said rollers and forming a yieldable jaw, an adjustably tensioned spring associated with said strip to tension the same, a pad of cushioning material forming a backing for the medial portion of the strip, and a movable jaw cooperating with said yieldable jaw to 115 clamp the work therebetween.

6. In a device of the character described, the combination of a pedestal, a lever pivotally supported intermediate its ends on said pedestal, a treadle-operated shaft, linkage connecting said shaft with said lever, a work-supporting plate mounted on said lever and having an edge forming a jaw, a yieldable 125 jaw mounted on said pedestal and cooperating with said movable jaw, and spring means associated with said lever to normally 130

urge said movable jaw into engagement with said yieldable jaw.

7. In a device of the character described, the combination with a supporting frame, of a channelled frame member secured thereto and having inturned, medially disposed flanges, strip guides mounted in the ends of said frame, a strip of pliable material extending around said guides and between the same and forming a yieldable jaw, one end of said strip being anchored to said frame, a spring connected to the other end of said strip, a rod mounted in said frame member and having adjustable, threaded connection with said spring to vary the tension thereof and hence the tension of said jaw, a pad of cushioning material secured to said inturned flanges, and a movable jaw mounted on said frame and cooperating with said yieldable jaw to hold the work therebetween.

In testimony whereof, I affix my signature.

JOSEPH F. HUEBSCH.
